UNITED STATES PATENT OFFICE.

EDWARD W. DRIEMEYER, OF CINCINNATI, OHIO, ASSIGNOR TO THE K-D LAMP COMPANY, A CORPORATION OF OHIO.

DESIGN FOR A VEHICLE LAMP.

Application filed October 29, 1924. Serial No. 11,221. Term of patent 3½ years.

To all whom it may concern:

Be it known that I, EDWARD W. DRIEMEYER, a citizen of the United States, residing in Cincinnati, in the county of Hamilton and State of Ohio, have invented a new, original, and ornamental Design for Vehicle Lamps, of which the following is a specification, reference being had to the accompanying drawing, forming part thereof.

The figure is a perspective of a vehicle lamp showing my new design.

I claim:

The ornamental design for a vehicle lamp as shown.

EDWARD W. DRIEMEYER.
